(57) CLAIM

The ornamental design for a headband, as shown and described.

DESCRIPTION

FIG. 1 is a perspective view of a headband, showing my design;

FIG. 2 is a perspective view thereof with the opening in an open position;

FIG. 3 is a front view thereof;

FIG. 4 is a rear view thereof;

FIG. 5 is a top view thereof, the bottom view being a mirror image of the top view;

FIG. 6 is a left side view thereof;

FIG. 7 is a right side view thereof;

FIG. 8 is a perspective view thereof in use; and,

FIG. 9 is a perspective view thereof in use with a mask coupled to the fastener.

Portions of the Headband are shown broken away to indicate indeterminate length.

The broken line showing is for illustrative purposes only and forms no part of the claimed design.
